UNITED STATES PATENT OFFICE.

ALBERT H. NELLER, OF FAIRFIELD, IOWA, ASSIGNOR TO LOUDEN MACHINERY COMPANY, OF FAIRFIELD, IOWA, A CORPORATION OF IOWA.

WIRE-STRAIGHTENER.

1,054,022.

Specification of Letters Patent.

Patented Feb. 25, 1913.

Application filed October 21, 1909. Serial No. 523,908.

To all whom it may concern:

Be it known that I, ALBERT H. NELLER, a citizen of the United States, residing at Fairfield, in the county of Jefferson and 5 State of Iowa, have invented a new and useful Improvement in Wire-Straighteners, of which the following is a specification.

My invention relates to machines for straightening wire from the coil, and it consists of means for holding a coil of wire in a vertical loosely hanging position and taking the wire to the straightening mechanism from the upper edge of the coil, also, of an improved form of the straightening apparatus, 15 and in other features set forth in this specification, and more definitely pointed out in the claims.

In the accompanying drawings forming a part of this specification, Figure 1 is a perspective of a machine embodying the features of my invention. Fig. 2 is an enlarged longitudinal section of the straightening mechanism, and a side view on the opposite side from Fig. 1, of the portion of the 25 frame to which it is attached, the ends of the framework being broken away. Fig. 3 is a transverse section on line 3—3 of Fig. 1. Fig. 4 is a cross section on line 4—4 of Fig. 3, the ends of the framework being 30 broken away. Fig. 5 is a transverse section on line 5—5 of Fig. 1. Fig. 6 is the same on line 6—6 of Fig. 1, the ends being broken away. Figs. 7 and 8 are sectional detail views which will be explained hereinafter.

Referring to the drawings, A represents a timber to which a post B and legs C are attached, forming in effect a frame or trestle. D is a roller mounted at one side of the 40 trestle on a laterally projecting horizontally disposed axle E, as shown most plainly in Fig. 7, which is a transverse section of the roller D near its outer end. This axle is preferably tubular and is driven into or 45 otherwise attached to the post B, just below the timber A.

The object of the roller D is to hold the coil of wire to be straightened in a vertical loosely hanging position, for delivery to the 50 straightening apparatus, and to assist in this it is preferably fitted with a flange d and with a guard F formed as shown, of a rod of iron having its ends brought together and driven into the tubular axle E.

The coil of wire W is placed upon the 55 roller D and one of its ends is passed around guide sheaves G and G', the former being attached by an iron to the post B near its lower end, and the latter, to iron plates M secured to the outer end of the timber A. 60

From the sheave G' the end of the wire is passed to the straightening apparatus which consists essentially of three geared wheels H, I and J, adjustably mounted so the wire may be passed between them. 65 These wheels are each provided with a deep groove in the center, as most plainly shown in Fig. 8, which is a horizontal section through the center of the wheel H, showing its immediate connections. The wheel H is 70 mounted on an axle which is preferably held in place by two straps of iron K, secured to the timber A, one on each side, with the axle between their upper ends. The wheel J is mounted on an axle secured 75 to a lever L which is pivoted to the timber A. It is preferably composed of a bar of iron having its lower end forked so that the wheel J may be mounted on an axle between the forks and that these ends may 80 straddle the upper edge of the timber A and be pivoted thereto.

The wheel I is mounted on an axle which is secured between the adjacent ends of two sets of iron straps N and O, one member of 85 each set being on each side of the wheel I. The other ends of the straps N are jointedly connected to the outer ends of the axle upon which the wheel H is mounted, and the other ends of the straps O are connected in a 90 similar manner to the outer ends of the axle upon which the wheel J is mounted.

The lower end of one of the forked ends of the lever L is extended down below the timber A and is provided with a spring 95 pressed pawl P which is adapted to engage and be held by a rack Q secured to the post B. The upper end of the lever is fitted with a hand piece R which is connected to the pawl by a rod r in the usual way. In 100 Fig. 1, the main part of the lever L passes on the rear side of the timber A, while in Fig. 2, it is shown broken away to show the wheel J.

It will be seen by moving the lever L 105 back and forth that the wheel J will be moved closer to or farther from the wheel H, and at the same time, the wheel I will

be raised and lowered. In bringing the wheels H and J closer together with the lever, and raising the wheel I, the space between them made by the grooves in the 5 wheels, will be increased so that the end of the coiled wire may be readily inserted therein. By bringing the lever back so as to move the wheel J away from the wheel H and thus lowering the wheel I, the bottom 10 of its groove will press the wire against the bottoms of the grooves in the wheels H and J, so as to take out the bend of the coil and leave the wire approximately straight, as shown in Fig. 2.

15 By separating the wheels H and J too far and bringing the wheel I down too much, a bend may be made in the wire in the opposite direction but this is regulated approximately by the pawl P and rack Q, 20 which may be set to hold the wheels in the proper position to straighten the wire. As a further means of adjustment, a guide sheave S is mounted in a standard T which is adjustably secured to the timber A. By 25 this means the sheave may be adjusted up or down so the wire in passing under it will be made approximately straight. It is necessary that the wheel I be set low enough to spring the wire slightly in the 30 opposite direction to make up for its recoil or its spring backward when released. This will bring the wire up against the sheave which may then be adjusted exactly to the proper position to properly straighten the 35 wire.

The adjustment of the standard T is preferably made by a coiled spring U and a thumb-screw V, the former being adapted to raise the standard T and the latter to 40 lower it. An adjustment sidewise may also be provided for if necessary. The wire is carried through the wheels by means of power applied to one of them, preferably to the wheel H. In Figs. 1 and 8 a crank X 45 is shown connected to the axle of wheel H by means of which the machine may be operated. The machine is also preferably provided with a gage and means for cutting off the wire in desired lengths. A piece of 50 hardened steel Y having a hole with a cutting edge through which the wire passes is secured to the upper portion of the standard T. Another piece of hardened steel 2 having a similar hole is pivoted to the 55 piece Y by means of a pin or axle 3 so the holes will coincide while in normal position. The lower end of the piece 2 is elongated and a lever 4 having a curved upper end 5 is pivoted to it. The wire being in 60 the hole, and the lever 4 being raised, the end 5 will come in contact with the side of the standard T and the cutter 2 will turn on its pivot 3 and will cause the cutting edge to shear the wire.

55 To provide for a gage, a bar 6, preferably

in the form of an angle or V in cross section to receive and hold the straightened wire, is affixed to the rear end of the timber A, and a gage 7 is adjustably secured to this bar. The gage is preferably fitted with a 70 clamping piece 8 adapted to catch over and slide on the bar 6 and a set-screw 9 to hold the gage in position on the bar. To hold the machine in position and to prevent it from upsetting with a heavy coil of wire 75 on the roller at one side, braces or stays 10 are secured to the post B and legs C. These braces are provided with an opening near the center through which a threaded hook bolt 11 having a threaded nut is passed. 80 A screw eye 12 is fastened to the floor or to a timber below and the hook of the bolt 11 is inserted in the eye of the screw as shown in Fig. 1. In straightening coils of wire of different sizes the guide sheave G may be 85 placed higher or lower on the post B to suit the size of the coil. Also, the guide sheave G' may be set in or out to suit the size of the coil by adjusting the plate M in or out on the timber A. In this way a coil 90 of wire of different sizes may be hung upon the roller D without having to be rewound or made to fit the roller and one of its ends passed around the guide sheaves G and G' and through the wheels H, I and J where 95 it is straightened, then through the holes in the cutter blades 2 and Y and to the gage 7, so that it may be cut in pieces of uniform lengths; or if wanted to straighten the wire only, the cutters and the gage may 100 be dispensed with. This is a simple easily operated machine and will do its work well either for straightening alone, or to straighten and cut the wire to lengths.

What I claim is:—

1. In a wire straightening machine, a frame, a roller having one free end mounted on an axle secured in a horizontal position to one side of the frame and adapted to receive and support a coil of wire at the 110 side of the frame in a vertical, loosely hanging position, and a series of wire straightening wheels vertically set on an upper part of the frame and adapted to receive the wire above the upper edge of the coil. 115

2. In a wire straightening machine, a frame, a roller having one free end mounted on an axle secured in a horizontal position to one side of the frame and adapted to receive and support a coil of wire at the 120 side of the frame in a vertical, loosely hanging position, a series of wire straightening wheels mounted in a vertical position on an upper part of the frame, and a grooved roller to guide the wire to the straightening 125 wheels above the upper edge of the coil.

3. In a wire straightening machine, a frame, a roller having one free end mounted on an axle secured in a horizontal position to one side of the frame and adapted to 130

receive and support a coil of wire at the side of the frame in a vertical, loosely hanging position, a flange on the outer end of said roller, and a series of wire straightening wheels vertically set on an upper part of the frame and adapted to receive the wire from above the upper edge of the coil.

5. In a wire straightening machine, a frame, a series of adjustably mounted 10 wheels adapted to straighten a wire when passed between them, a roller mounted on a tubular axle secured to the frame and having a guard at its outer end consisting of a rod bent and having its ends doubled 15 together and driven into the outer end of the tubular axle, so as to hold the coil on the roller and in position to deliver to the wire straightening wheels.

6. In a wire straightener, three gear 20 wheels provided with a groove in their centers and mounted on axles in the same lateral alinement so the gears will mesh together, the wheel at one end of the series being mounted on a stationary axle, and the 25 axle of the wheel at the opposite end being secured to a lever pivoted to the frame of the machine, the movement of which lever will cause the latter wheel to move toward or away from the former, the central wheel being mounted on an axle pivoted to the inner ends of two sets of straps, the outer ends of said straps being pivoted respectively to the axle of the stationary wheel and to the axle of the wheel secured to the 30 lever, so that the movement of the lever will cause the central wheel to rise and fall, means to guide the wire into the groove between the wheels, and means to rotate the wheels and thus to straighten the wire.

7. In a wire straightener, three gear 40 wheels provided with a groove in their centers and mounted on axles in the same lateral alinement so the gears will mesh together, the wheel at one end of the series being mounted on a stationary axle, and the 45 axle of the wheel at the opposite end being secured to a lever pivoted to the frame of the machine, the movement of which lever will cause the latter wheel to move toward or away from the former, the central wheel being mounted on an axle pivoted to the inner ends of two sets of straps, the outer ends of said straps being pivoted respectively to the axle of the stationary wheel 50 and to the axle of the wheel secured to the lever, so that the movement of the lever will cause the central wheel to rise and fall, means to guide a wire into the groove between the wheels, and means to rotate the 55 wheels and thus to straighten the wire.

8. In a wire straightener, three gear 60 wheels provided with a groove in their centers and mounted on axles in the same lateral alinement so the gears will mesh together, the wheel at one end of the series 65

being mounted on a stationary axle, and the axle of the wheel at the opposite end being secured to a lever pivoted to the frame of the machine, the movement of which lever will cause the latter wheel to move toward or 70 away from the former, the central wheel being mounted on the axle pivoted to the inner ends of two sets of straps, the outer ends of said straps being pivoted respectively to the axle of the stationary wheel and to the 75 axle of the wheel secured to the lever, so that the movement of the lever will cause the central wheel to rise and fall, a roller to hold a coil of wire, means to guide the end of the wire into the groove between the 80 wheels, and means to rotate the wheels and thus to straighten the wire.

9. In a wire straightener, three gear 85 wheels provided with a groove in their centers and mounted on axles in the same lateral alinement so the gears will mesh together, the wheel at one end of the series being mounted on a stationary axle, and the axle of the wheel at the opposite end being secured to a lever pivoted to the frame of 90 the machine, the movement of which lever will cause the latter wheel to move toward or away from the former, the central wheel being mounted on an axle pivoted to the inner ends of two sets of straps, the outer ends 95 of said strap being pivoted respectively to the axle of the stationary wheel and to the axle of the wheel secured to the lever, so that the movement of the lever will cause the central wheel to rise and fall, means to 100 guide a wire into the groove between the wheels, and a crank secured to the axle of one of the wheels to rotate them and thus to straighten the wire.

10. In a wire straightener, a frame, a roller 105 adapted to carry a roll of wire secured to one side of the frame, a gear wheel having a groove in its center mounted upon a stationary axle upon the frame, a lever pivoted to the frame, a gear wheel having a groove 110 in its center mounted on an axle secured to the lever so the movement of the lever will cause it to move toward and away from the stationary wheel, a central gear wheel also having a groove in its center mounted on an 115 axle jointedly secured to the adjacent ends of two sets of straps, the opposite ends of said straps being jointedly secured respectively to the lever and to the axle of the stationary wheel, so that the movement of the 120 lever will raise and lower the central wheel, said wheels being in alinement laterally so they will mesh with each other, means for guiding the wire into the groove between the wheels, and means to rotate the 125 wheels and thus to straighten the wire.

11. In a wire straightener, a frame, a roller 130 adapted to carry a roll of wire secured to one side of the frame, a gear wheel having a groove in its center mounted upon a station-

ary axle upon the frame, a lever pivoted to the frame, a gear wheel having a groove in its center mounted on an axle secured to the lever so the movement of the lever will cause it to move toward and away from the stationary wheel, a central gear wheel also having a groove in its center mounted on an axle jointedly secured to the adjacent ends of two sets of straps, the opposite ends of 10 said straps being jointedly secured respectively to the lever and to the axle of the stationary wheel, so that the movement of the lever will raise and lower the central wheel, said wheels being in alinement laterally so 15 they will mesh with each other, means for guiding the wire into the groove between the wheels, and means to rotate the wheels, a pawl secured to the lower end of the lever, and a rack secured to the frame adjacent to 20 the pawl so as to engage it and thus to hold the wheels in proper relation to each other to straighten the wire.

11. In a device of the character described, a frame, a roller on one side of the frame 25 adapted to carry a coil of wire, straightening wheels mounted on the top of the frame, means to conduct the wire into and through the wheels, a standard carrying a guide roller secured to the frame in the rear of 30 the straightening wheels, a spring interposed between the upper part of the standard and the frame piece on which it is mounted, and a thumb-screw passed through the lower part of the standard and bearing 35 against the lower side of the frame.

12. In a device of the character described, having a horizontally disposed roller mounted on one side of a frame, and having one free end adapted to receive and support 40 a coil of wire in a loosely hanging vertical position, wire straightening wheels mounted on the upper part of the frame, means to conduct the wire through the wheels, and a guide roller to further adjust the alinement 45 of the wire after passing through the straightening wheels.

13. In a device of the character described, having a horizontally disposed roller mounted on one side of a frame, and having one 50 free end adapted to receive and support a coil of wire in a loosely hanging vertical position, wire straightening wheels mounted on the upper part of the frame, means to conduct the wire through the wheels, a guide 55 roller mounted on a standard secured to the frame to further adjust the alinement of the

wire after passing through the wheels, and a wire cutter secured to the standard.

14. In a device of the character described, having a horizontally disposed roller mounted on one side of a frame, and having one free end adapted to receive and support a coil of wire in a loosely hanging vertical position, wire straightening wheels mounted on the upper part of the frame, means to 60 conduct the wire through the wheels, a cutter placed in the path of the wire, an extended bar in line with the wire after passing through the straightening wheels, and a gage adjustable upon the bar to set the 65 lengths of the wire to be cut.

15. In a device of the character described, having a horizontally disposed roller mounted on one side of a frame, and having one free end adapted to receive and support a 70 coil of wire in a loosely hanging vertical position, wire straightening wheels mounted on the upper part of the frame, means to conduct the wire through the wheels, and a bar extended in line with the wire after 75 passing through the straightening wheels made with a groove or recess in its upper face to receive and support the straightened wire.

16. In a wire straightening machine having wire-straightening means mounted thereon, a horizontally disposed roller having a free end and adapted to receive and support a coil of wire in a loosely hanging vertical position, mounted on one side of the 80 machine, and means to guide one end of the coiled strands of the wire into the straightening mechanism.

17. In a device of the character described, a horizontally disposed timber carrying wire 85 straightening wheels and supported by a vertical post, a roller having a free end to receive and support a loosely hanging coil of wire, mounted on an axle set in a horizontal position at one side of the timber and 90 post, and approximately at right angles thereto, and sheaves for receiving and guiding a strand of the wire into the straightening wheels, one of the sheaves being mounted on the vertical post and the other secured 95 to the horizontal timber in position to suit the size of the coil of wire.
